UNITED STATES PATENT OFFICE

132,603

DESIGN FOR A PRESS DRILL OR THE LIKE

George R. Wilcox, Greenfield, Mass., assignor to
Millers Falls Company, Greenfield, Mass., a
corporation of Massachusetts

Application December 11, 1940, Serial No. 97,254

Term of patent 14 years

To all whom it may concern:

Be it known that I, George R. Wilcox, a citizen of the United States, of Greenfield, county of Franklin, State of Massachusetts, whose post-office address is 9% Millers Falls Company, Greenfield, Franklin County, State of Massachusetts, have invented a new, original, and ornamental Design for a Press Drill or the like, of which the following is a specification, reference being had to the accompanying drawing, forming part thereof, in which:

Fig. 1 is a side elevational view of a press drill showing my new design; and

Fig. 2 is an end view looking down from the top of Fig. 1.

Fig. 3 is a sectional view taken on the line 3—3 of Fig. 1.

The handle comprises a main multi-sided barrel member which is transparent and discloses the inner ribbed barrel. The quill tapers down to the main shank of the tool and has a contrasting color from that of the inner barrel and the shank. A cap at the top of the handle is spaced from the barrel by a band, the cap and band also having contrasting colors.

I claim:

The ornamental design for a press drill or the like, as shown and described.

GEORGE R. WILCOX.
